UNITED STATES PATENT OFFICE.

JESSE DITSON, OF LITTLETON, COLORADO, ASSIGNOR TO INGERSOLL-RAND COMPANY,
OF JERSEY CITY, NEW JERSEY, A CORPORATION OF NEW JERSEY.

FORGING MACHINE FOR COAL-CUTTER PICKS.

Application filed September 26, 1925. Serial No. 58,722.

To all whom it may concern:

Be it known that I, JESSE DITSON, a citizen of the United States, and a resident of Littleton, in the county of Arapahoe and State of Colorado, have invented certain Forging Machines for Coal-Cutter Picks, of which the following is a specification accompanied by drawings.

This invention relates to forging machines, but more particularly to a clamping device for machines of this type.

In forging and resharpening coal picks and other similar tools, considerable difficulty is sometimes caused by the tendency of the stock to slip out from between the dies during the forging operation. This is particularly the case in tools having a tapered bit which requires the forming faces of the dies to be set at an angle to each other and which angle corresponds to the desired angle of the bit. It has been found, however, that by means of a suitable automatic clamping device the pick or other article to be forged may be held firmly in position and that by so doing the bit of the tool may be drawn out to a thin edge or point.

The objects of the invention are to prevent slipping of the coal pick from between the forging dies during the forging operation and to enable the bit of the coal pick to be drawn out to a thin edge or point and to automatically release the pick or other article to be forged after the forging operation is completed.

Other objects will be in part obvious and in part pointed out hereinafter.

The invention consists of the combinations of elements, features of construction and arrangement of parts having the general mode of operation substantially as hereinafter described and more particularly pointed out in the appended claims and illustrated in the accompanying drawings, in which—

Figure 1 is a side view in elevation of so much of a drill sharpener as will serve to illustrate the invention, and

Figure 2 is a front view in elevation partly in section of a drill sharpener illustrating the manner in which a coal pick may be held against slipping from between the forming dies.

Referring to the drawings, the invention is shown embodied in a drill sharpener

having a cross head A and a main cylinder B. In this instance the cross head A is adapted to reciprocate with respect to the main cylinder B and has a recess C extending along one side to receive a top die holder D, which is held in position by means of a top clamping plate E secured to the cross head by means of screws F. Similarly the main cylinder B is recessed as at G to receive a bottom die holder H which in this instance has an outwardly extending projection J and is held in position by a bottom clamping plate K, which like the clamping plate E, is also secured in position by means of screws F. A bottom forming die L is secured to the bottom die holder H and held in position by a screw O. A somewhat similar top forming die P is inserted in a recess Q of a top die holder and like the bottom die L is also held securely in position by the screw O. The dies L and P are in this instance set at an angle to each other to form a corresponding angle on a bit R on a coal pick S. In order to provide sufficient support for the pick S during the forging operation a side face of the bottom die holder H is recessed to form a supporting face T upon which the pick or other tool to be forged may rest during the forging operation.

Means are provided for preventing the pick S to be forced outwardly from between the dies when the top die P descends upon said pick. To this end an eccentric member U is mounted on the projection J of the bottom die holder H and is secured to said projection by means of a pivot V. The pivot V may be of any suitable form, but in this instance is in the form of a bolt extending through the member U and through the projection J. The eccentric member U has a serrated engaging surface W which is so formed with respect to the pivotal point of the member U that when the top die descends, the serrated surface W will firmly grip the shank of the pick S.

In order to manipulate the eccentric member U either manually or automatically, a lifter X projects through a recess Y in the top clamping plate E and has a hook portion Z pivotally engaging the eccentric member U. A collar b is formed on the lifter X near the hook portion Z and forms a seat for a compression spring c arranged about said lifter. The recess Y is of somewhat

larger diameter than the outside diameter of the spring *c* so that when the cross head *A* is raised, the spring *c* may remain upon the collar *b*. In order to form an abutment for the opposite or upper end of the spring *c*, the recess *Y* is reduced for a portion of its length to form a shoulder *d* against which the spring *c* may bear when the cross head *A* descends. The free end of the lifter *X* is preferably screw threaded to receive a nut *e* against which the top face of the top clamping plate *E* may strike for automatically rocking the eccentric *U* into releasing position when the cross head *A* is raised. The lifter *X* is preferably of sufficient length to permit reciprocation of the cross head *A* within certain limits without rocking the eccentric member *U* about its pivot. If desired the eccentric member *U* 20 may be rocked manually by raising the lifter *X*.

For further forming operations of the bit *R*, a bottom forming block *f* may be arranged in the recess *G* and an opposed top forming block *g* may be inserted in the recess *C*. The blocks *f* and *g* are preferably held in position by clamping plates *h* which like the clamping plates *E* and *K* are held firmly in position by screws *F*.

30 In the operation of the device assuming that the stock for the pick *S* is about to be placed in position between the dies *L* and *P* and that the eccentric is held in the released position heretofore described, the cross head *A* may then be lowered to form the bit *R*. Immediately after the beginning of the downward stroke of the cross head *A*, the lifter *X* will be released and due to its own weight and that of the eccentric member *U* will cause the eccentric member to drop to the retaining position shown in Figure 1. As the cross head descends and immediately prior to the blow of the die *P* upon the bit *R*, the shoulder *d* of the recess *Y* will bear against the spring *c* and thus transmit pressure through said spring upon the collar *b* of the lifter *X* and force the eccentric member *U* more firmly into engaging position upon the shank of the pick *S*.

40 50 By means of this device the pick *S* will be held firmly against outward movement. The force of the dies acting against the bit *R* will cause the eccentric to grip the pick

S more firmly thus enabling the bit *R* to be drawn out to a thin edge.

55

I claim:

1. In a machine for forging a pick, the combination of a stationary main cylinder with a reciprocatory cross head, a top die holder on the cross head, a top forming die carried by said die holder, a bottom die holder secured to the main cylinder, a bottom die secured to the bottom die holder, an eccentric member pivoted on the bottom die holder for clamping a pick immovably on the bottom die, and a lifter controlled by the cross head for holding the eccentric member in clamping position and for rocking the eccentric member to releasing position.

70

2. In a machine for forging a pick, the combination of a stationary main cylinder with a reciprocatory cross head, a top die holder on the cross head, a top forming die carried by said die holder, a bottom die holder secured to the main cylinder, a bottom die secured to the bottom die holder, an eccentric member pivoted on the bottom die holder for clamping a pick against the bottom die, said eccentric having a serrated engaging surface, and a lifter pivotally secured to the eccentric member and controlled by the cross head for holding the eccentric member in clamping position and for rocking said member to releasing position.

85

3. In a machine for forging a pick, the combination of a stationary main cylinder with a reciprocatory cross head, a top die holder on the cross head, a top forming die carried by said die holder, a bottom die holder secured to the main cylinder, a bottom die secured to the bottom die holder at an oblique angle to the top die, an eccentric member mounted pivotally on the bottom die holder and having a serrated engaging surface for preventing removal of a pick from the bottom die, a lifter controlled by the cross head for holding the eccentric member in engaging position, and a spring for transmitting pressure from the cross head for holding said member in engaging position.
